UNITED STATES PATENT OFFICE.

ZOLTAN TROTZER, OF BUDAPEST, HUNGARY.

ELECTRIC WATER HEATER.

Application filed November 1, 1921. Serial No. 512,100.

To all whom it may concern:

Be it known that I, ZOLTAN TROTZER, director, a citizen of Hungary, residing at Budapest, in Hungary, have invented certain new and useful Improvements in Electric Water Heaters, of which the following is a specification.

My invention relates to improvements in electric water-heaters and more especially to such heaters to be used in direct connection with water supply pipes, the object being to draw according to the requirements cold or hot water from the apparatus.

For this purpose I provide besides the choked water passage leading along the heating body another direct channel shunting the former, being free from throttling and insert in the said direct water-channel a valve positively coupled with the switch arranged in the electric circuit of the heating body, to close the circuit if the valve is pressed by the water-pressure against its seat closing thereby the direct water channel.

In the annexed drawing I have shown as an example an embodiment of my invention in diagrammatic sectional elevation.

Fig. 1 shows the parts in their relative position for the delivery of cold water and

Fig. 2 in the position delivering hot water.

With reference to the drawings:

1 is a receptacle with a central tube 2 and 3 is an electric resistance heater located in the annular space between receptacle 1 and tube 2. One terminal of the heating resistance is connected with contact 4 and the other terminal with one wire of a cable 30 leading to an electric current source, while the other wire of said cable is connected to contact 5.

A tubular member 6 surrounding the lower end of the central tube 2 projecting from the bottom of the apparatus and adapted to slide thereon is provided with a flange 45 7 and a contact disc 8. A spring 9 tends to press the tubular member 6 together with the contact disc 8 into its upper position shown in Fig. 1.

12 is a valve and 11 a rod secured thereto and bearing against a perforated plate 10 located near the delivery end of the tubular member.

The washer 13 on the upper end of the central tube 2 serves as seat for the valve 12.

55 The heating body 3 divides the annular spaces between the receptacle 1 and the tube

2 into two concentric annular chambers 14 and 15 communicating at their bottom by means of the opening 16 in the heating body 3. The inner annular chamber 15 60 communicates at its top by means of the opening 17 of tube 2 diametrically opposed to opening 16 with the interior of tube 2. Chamber 15 is closed at 18 and the inlet connecting branch 19 extends to the cover 65 18. Thus the water flowing through the connecting branch 19 can enter the inner chamber 14 only through the small opening 20 diametrically opposite to opening 16.

The inlet connecting branch 19 is provided with a stuffing lining 21 to ensure a watertight connection with the spigot 22.

In operation the water entering from the spigot the connecting branch 19 flows round the valve disc 12, enters through opening 23 the interior of the central tube 2, and leaves the apparatus through the delivery end 26 of the tubular member 6 without coming in touch with the heating body 3. The electric current being interrupted between the contact disc 8 and the contacts 4 and 5 respectively, cold water is delivered without throttling.

If however hot water is required, the tubular member 6 is slightly pulled downwards against the pressure of spring 9, thereby throttling the passage of the water below the valve 12 and the pressure acting upon the valve overcomes the spring 9 and presses this latter against its seat 13. By 90 means of rod 11 and the perforated plate 10 the tubular member 6 will be depressed into its lowest position shown in Fig. 2, where it will be held against the pressure of spring 9. In this position contact disc 95 8 closes with contacts 4 and 5 the circuit through the heating body 6. The water is compelled to pass through the small bore 20 into the outer annular space 14, circulates from top to bottom along the outer 100 surface of the heating body and enters at the opposite side through aperture 16 the inner annular space 15. In this latter the water flows along the inner surface of the heating body from bottom to top and is 105 delivered at the opposite side through opening 17 into the central tube 2.

Owing to the choking action of the small bore 20, the pressure acting upon valve 12 will be maintained and at the same time the 110 quantity of the water passing the apparatus reduced in a measure to ensure the heating

to the desired temperature. This latter can be regulated by adjusting the throttling screw 27.

By closing the spigot, the pressure acting upon valve 12 is removed and the spring 9 lifts the tubular member 6 with the contact disc 8, interrupting thereby the electric circuit.

Owing to the large diameter of the tube 2 no siphon effect will draw off the water from the spaces 14 and 15 and the heating body 3 will be kept constantly under water.

The interruption of the circuit at the contacts 4, 5 is a momentary one.

As it is to be seen the apparatus adjusts itself automatically for the delivery of cold water needed more often and the cold water will be delivered just as freely as if no heating apparatus were connected to the tap.

The apparatus does not interfere in any way with the ready use of cold water and throttles the water flow only if hot water is required.

Any suitable means may be provided for connecting the heating apparatus with the water tap.

Having now fully described and ascertained my said invention and the manner in which it is to be performed, I declare that what I claim is:

1. In an electric water heating apparatus, a receptacle, an electric heating body therein, a water passage leading along said heating body, and constructed to permit a relatively slow flow of water, another water passage shunting the former passage and constructed to permit a relatively rapid flow of water, a valve inserted in said shunting passage, coupled with a switch inserted in the circuit of the heating body and means tending to open the said valve and the switch.

2. In an electric water heating apparatus, a receptacle, an electric heating body therein, a water passage leading along said heating body, and constructed to permit a relatively slow flow of water, an adjustable throttling screw inserted in said water passage, another water passage shunting the former passage and constructed to permit a relatively rapid flow of water, a valve inserted in said shunting passage coupled with a switch inserted in the circuit of the heating body and means tending to open the said valve and the switch.

tively slow flow of water, an adjustable throttling screw inserted in said water passage, another water passage shunting the former passage, and constructed to permit a relatively rapid flow of water, a valve inserted in said shunting passage coupled with a switch inserted in the circuit of the heating body and means tending to open the said valve and the switch.

3. In an electric water heating apparatus, a receptacle, an electric heating body therein, a water passage leading along said heating body, and constructed to permit a relatively slow flow of water, a central outlet tube shunting the former passage, and constructed to permit a relatively rapid flow of water, a valve inserted in said outlet tube, a tubular member adapted to slide on said outlet tube and coupled with a switch inserted in the circuit of the heating body and means tending to lift the said tubular member and valve.

4. In an electric water heating apparatus, a receptacle, an electric heating body therein, a water passage leading along said heating body within the receptacle, and constructed to permit a relatively slow flow of water, an adjustable throttling screw inserted in said water passage, a central outlet tube shunting the former passage and projecting from the bottom of said receptacle, said tube permitting a relatively rapid flow of water, a valve inserted in said outlet tube, a tubular member adapted to slide on the projecting end of the outlet tube and coupled with a switch inserted in the circuit of the heating body and a spring tending to lift said tubular member.

In testimony whereof I affix my signature in presence of two witnesses.

ZOLTAN TROTZER.
